UNITED STATES PATENT OFFICE.

FRANCIS E. COLLINSON, OF LONDON, ENGLAND, ASSIGNOR OF ONE-HALF TO TAYLOR
INSTRUMENT COMPANIES, OF ROCHESTER, NEW YORK, A CORPORATION OF NEW
YORK.

BAROMETER.

1,206,094.

Specification of Letters Patent. Patented Nov. 28, 1916.

Application filed August 12, 1914. Serial No. 856,322.

To all whom it may concern:

Be it known that I, FRANCIS E. COLLINSON, of London, England, have invented certain new and useful Improvements in 5 Barometers; and I do hereby declare the following to be a full, clear, and exact description of the same, reference being had to the accompanying drawings, forming a part of this specification, and to the reference-characters marked thereon.

10 My invention has for its object to improve the construction of aneroid barometers, in order to afford means for more readily reading the instrument and determining the 15 character of the weather, as indicated by the position of the indicator or hand upon the dial.

More particularly, the invention contemplates the provision of a novel form of supplemental index that is manually adjustable with relation to the indicator and can be set at any position of the indicator in order to subsequently show the movement of the 20 indicator from said position, and also the condition of weather that would usually result in or follow such a position of the indicator.

To these and other ends the invention consists of certain improvements and combinations of parts all as will be hereinafter more 25 fully described, the novel features being pointed out in the claim at the end of the specification.

In the drawings: Figure 1 is a plan view 30 of a barometer constructed in accordance with my invention, and Fig. 2 is a sectional view on the line 2^a—2^a of Fig. 1.

Similar reference characters throughout the several figures indicate the same parts.

35 In the embodiment of the invention shown, A designates the casing within which is contained the operating mechanism, such as generally employed in this type of device.

B designates a dial which is preferably 40 stationary, although it may be otherwise arranged within the casing, and provided with the usual barometer indications. Coöperating with the dial B is an indicator C which is suitably connected and controlled by the 45 operating mechanism contained within the casing, as usual in barometer construction.

It is desirable to be able to ascertain in connection with any reading, the direction and extent of movement of the indicator 50 from its position when the last previous

reading was taken and this is generally accomplished by means of a supplemental hand that is manually adjustable and can be positioned so as to coincide with the mechanism controlled indicator.

According to my present invention, instead of employing a hand or similar indicator, I make use of an index plate that is rotatable with relation to the indicating dial. Preferably, the index plate is of circular formation as indicated at D, although the plate may be otherwise constructed and it may be cut away to afford open portions E on either side of a central strip F, by which it is secured in position. The casing 60 is provided with a transparent cover G preferably of glass which is held in place by means of the bezel H, the cover G being provided with a central opening to receive the rotatable arbor I. The index plate is fixedly 65 mounted at the inner end of the arbor I, being disposed preferably between the cover G and the dial, and may be turned in opposite directions by means of a knurled head J provided on the arbor I.

80 The index plate D carries an indication K, arranged at one edge and adapted to be brought into alinement with the indicator C as shown in Fig. 1, to show the extent of movement of the indicator when it has been 85 operated, for example, to the position shown in dotted lines. The index plate also is provided with various weather indicia on opposite sides of the indicator K as for instance an arrow pointing to the right, on 90 one side, together with the words "Rising for colder, less wind or dry weather," and on the other side an arrow pointing in the opposite direction with the words "Falling for warmer, more wind or wet weather," 95 the words or descriptive matter extending and reading circularly with respect to the axis of the index plate. One of the advantages of such a construction lies in the rapidity and ease with which an instrument can be read correctly. For instance, with the index plate in the position shown in Fig. 1 and with the indicator in the position shown in dotted lines, it is immediately apparent to the observer that the indicator 100 calls for falling weather with the probability of increased winds or wet weather and in this manner, the descriptive words showing the character of weather to follow are 105 always immediately over the indicator and 110

so positioned that they can be read easily, without confusion. This is of great advantage, especially with persons who are not so well versed in the use of a barometer or the relation of its readings to weather conditions. The index plate can, of course, be provided with additional instructive data that will assist the user in understanding the operation of the instrument, and the essential feature of my invention resides in having such descriptive data arranged on an index plate that is movable and carries a supplemental indication that can be brought to coincide with any position of the indicator.

I claim as my invention:

A barometer comprising a stationary dial and a movable indicator, an annular or ring-like index plate rotatable with relation to said dial and provided on its face with weather indicia extending or reading circularly of the axis of the index plate, the indicator being visible beyond the outer edge and within the inner edge of the index plate.

FRANCIS E. COLLINSON.
